UNITED STATES PATENT OFFICE.

CHARLES P. LAWSON, OF BROCTON, NEW YORK.

COMBINED ELECTRIC INCANDESCENT LAMP AND REFLECTOR.

1,127,903.

Specification of Letters Patent.

Patented Feb. 9, 1915.

Application filed March 10, 1914. Serial No. 823,734.

To all whom it may concern:

Be it known that I, CHARLES P. LAWSON, a citizen of the United States of America, and resident of Brocton, in the county of 5 Chautauqua and State of New York, have invented certain new and useful Improvements in Combined Electric Incandescent Lamps and Reflectors, of which the following is a specification.

10 This invention relates to illumination and particularly to a combined incandescent electric lamp and reflector.

An object of this invention is to provide 15 means associated therewith for reflecting the light effectively, the said invention contemplating the provision of an internally positioned reflector within the lamp and the coating of the upper portion of the lamp, 20 on its outer surface, so that the said coating will act as a reflector and coact with the internally positioned reflector, so that the efficiency of the lamp may be increased and the illuminating effect thereof augmented.

25 A still further object of the invention is to provide a novel lamp, the configuration of which increases the effective reflecting surface as compared with lamps now in ordinary use without materially increasing the 30 cost of production.

With the foregoing and other objects in view, the invention consists in the details of construction and in the arrangement and combination of parts to be hereinafter more 35 fully set forth and claimed.

In describing the invention in detail, reference will be had to the accompanying drawings, forming part of this specification wherein like characters denote correspond- 40 ing parts in the several views, and in which—

Figure 1 illustrates a view in elevation, the same being broken away to show the interior construction of the internal reflector; and Fig. 2 illustrates a sectional view 45 through the film support.

In these drawings 1 denotes the ordinary lamp head threaded to fit in a screw socket or the head may be otherwise formed. The 50 globe or glass part 2 of the lamp is secured to the head as in ordinary construction and the said globe or glass part of the lamp is here shown as of the ordinary pear shaped

container for the filament and intermediate the length of the said glass portion a circumferentially hollow flange 3 is formed, 55 the same being integral with the other portion of the body. As shown in the drawing, the flange is produced by the formation of a series of compound curves and that portion 60 designated by the numeral 4 has its under surface preferably concaved and the general contour of the said flange is slightly depending. The external surface of the body is coated with reflecting material 5, such as 65 quick-silver, the said coating extending from the head and terminating at the lower edge of the flange so that the upper portion of the lamp constitutes a reflector, and by reason of the provision of the flange the area 70 covered by the reflector is relatively greater than by the use of lamps of ordinary construction.

The filament support 6 within the lamp constitutes a reflector and consists of a shaft 75 or column extending downwardly from the head, the said column being hollow and the external surface thereof being flared from the head for a portion of its length, the said external surface being then tapered to the 80 lower end and terminating in a point by reason of which shadows are obviated.

The external surface of the filament support 6 has longitudinally disposed ribs or 85 corrugations 7 acting as prisms for diffusing light and the internal surface of the filament support has a coating 9 of quick-silver or other material having qualities of reflection so that the same will reflect the light and coact with the reflector of the body. 90

The film 8 may be of any appropriate type and is shown as secured to the filament support in known manner.

It will be observed that the post having reflecting means herein described may be 95 used in lamps other than those described herein.

I claim—

In an incandescent electric lamp, a head, a body attached thereto, said lamp body 100 having a compound curve intermediate its length forming a flange, the under surface of the said flange being concaved, a reflecting coating on the outer surface of the body extending from the head to the flange there- 10 of, a filament support depending from the

head, said filament support being flared for a portion of its length and tapered to the lower end and terminating in a point, ribs on the outer surface of the filament support,
5 said filament support being hollow, and reflecting material coating the internal surface of the filament support.

In testimony whereof, I affix my signature in the presence of two witnesses.

CHARLES P. LAWSON.
